UNITED STATES PATENT OFFICE.

EDWIN BRYAN DONKIN, OF BERMONDSEY, ENGLAND.

ROTARY PUMP.

SPECIFICATION forming part of Letters Patent No. 298,952, dated May 20, 1884.

Application filed August 13, 1883. (No model.) Patented in England January 13, 1883, No. 216; in France July 12, 1883, No. 156,519; in Belgium July 26, 1883, No. 62,135, and in Germany July 29, 1883.

To all whom it may concern:

Be it known that I, EDWIN BRYAN DONKIN, a subject of the Queen of Great Britain, residing at Southwark, Park Road, Bermondsey, 5 England, have invented certain new and useful Improvements in Rotary Pumps and Engines, (for which I have received Letters Patent in Great Britain, No. 216, dated January 13, 1883; in France, No. 156,519, dated July 10 12, 1883; in Belgium, No. 62,135, dated July 26, 1883, and in Germany, dated July 29, 1883,) of which the following is a specification.

This invention has for its object to improve that class of rotary pumps or engines, in which 15 a piston is carried by the pin of a crank made to revolve in a casing of a form approaching somewhat to the cardioidal form. By my improvements I am able to construct such pumps or engines with larger inlet and outlet ports 20 than heretofore, and am also able to better control the movement of the piston.

In the drawings hereunto annexed I have shown examples of pumps or engines constructed according to my invention.

25 Figure 1 is a transverse section, and Fig. 2 a longitudinal section, of one form of the pump or engine. Figs. 3 and 4 are similar views of a modified form of this pump or engine, and Figs. 5 and 6 are similar views of another 30 form, and Fig. 7 a transverse section of another modification. Figs. 8, 9, and 10 show the piston and guides in several successive positions. Figs. 11, 12, and 13 show details of the piston and guides in the double arrangement represented by Fig. 7.

In Figs. 1 and 2, A is the casing or cylinder. Its inner surface is in transverse section, approximately, a cardioid curve—that is, a curve along which any point upon a circle is carried when that circle is caused to roll around a second stationary circle of equal diameter. B is an oblong piston, through the center of which passes a crank-pin, C, carried by an axis, D, the center of which would coincide 40 with the center of the stationary circle above mentioned. The radial distance between the central line of the axis D, and the central line of the crank-pin is made somewhat less than the radius of the above-mentioned circle, and

the extreme point of the inward bend of the 50 cardioid curve is also cut off, as shown, so that the piston B may at the center be of sufficient thickness to give it the requisite strength. As the piston is carried round by the crank it is caused to make a half-revolution for each complete revolution of the crank-axis. The ends 55 of the piston are made to fit closely up to the ends of the casing, and the curve of the casing is such that the edge of the piston which is at any time farthest from the inward bend 60 of the casing always fits up to the side of the casing in whatever position the crank may be. When the piston is in the position shown at Fig. 1, it is at right angles to a line radial to the axis which passes through the center of 65 the crank-pin, and the extremity of the inward bend, A^x, of the casing is made to fit up to the center of the top side of the piston. The piston is made to taper from its center to its two side edges, and the inward bend of the 70 casing is so shaped that when the crank-axis is revolved and the piston carried round by the crank-arm, one side of this portion A^x of the casing always fits against one side of the piston until the piston comes into a position 75 at right angles to that in which it is shown. The inward bend of the casing then fits to the edge of the piston. A still further movement of the piston brings its opposite side into contact with the other side of this portion A^x of the 80 casing, and so the piston is carried round continuously, making, as before stated, half a revolution for each complete revolution of the crank-shaft.

E is an inlet-port for admitting air or other 85 fluid to the casing, and F the outlet-port by which it is expelled from the casing. The inward bend of the casing separates these two ports, and, always fitting to the piston, as above described, prevents the passage of fluid directly from one to the other. It will be seen that by making the casing to bend inward in the manner shown, and always fit to the piston at this point, that ports of very large size 90 may be made use of, whereas if the casing did not at this point fit to the piston the size of ports which could be used would be very restricted.

In order to control the movement of the piston as it is carried round by the crank-pin, so as to keep its ends always close to the sides of the casing without rubbing against them, I 5 control the movements of the piston in the following manner: The crank-pin C is made to project from a disk, G, on the axis D. This disk is received in a recess at one end of the casing A. The other end of the crank-pin 10 passes through a disk, H, which is concentric with the crank-axis, and which is free to revolve in a corresponding hole in the opposite end of the casing. A tubular neck projecting from the end of the piston also passes through 15 this disk. Outside the disk it has upon it a boss, from which project rods I. These at their ends have projections J, extending from them parallel with the crank-pin, and these carry pairs of parallel guide-bars K, in the 20 form of a right-angled cross. One pair of guide-bars is parallel with the piston, and the other at right angles to it. Between each pair of guide-bars is an oblong block, L, turning on a pin, M, carried by a casing, A', fixed to 25 the end of the casing A. The pins M are on opposite sides of and equidistant from the crank-axis. A radial line drawn through the extremity of the inward bend of the cardioid curve passes through the center of one pin. 30 The other is on the opposite side of the crank-axis. Both of them are at the same distance from the axis as the crank-pin that carries the piston. The two pins M are connected by a bar, N. The crank-pin has at its end an arm, 35 C^x, carrying a pin which is concentric with the crank-axis, and this pin is received in a bearing formed to receive it in the center of the bar N. As the piston is carried round by the crank-pin, the blocks L are turned on the 40 pins M, each making a half-turn for every complete revolution of the crank; and in order that the ends of the blocks may not strike one against the other as they revolve the blocks are at their ends cut away on one side, so as to reduce 45 them to half the thickness of their central part, and so that the extreme ends of one block are in a different plane to the extreme ends of the other block, as shown in Fig. 11. In this way blocks of longer length can be used 50 than would otherwise be practicable. The end of the casing which receives the disk H is made in two parts, to enable the disk H to be put into place between them.

In the modification shown at Figs. 3 and 4 55 no casing A' is used; but the guide-blocks L and the pins which carry them are on the inside of one end of the casing A. The guides K are fixed directly to the piston, and the piston is made sufficiently thick to contain the 60 return-crank C' within it. The same letters of reference are marked on the parts of these figures as in Figs. 1 and 2.

In the modification shown at Figs. 5 and 6 65 the construction is the same as shown at Figs. 1 and 2, except that the tubular neck at the end of the piston, which passes through the

disk H, has upon it an internal toothed wheel, O, which gears with a fixed toothed wheel, P, carried by the interior of the end of the casing A', this toothed wheel being concentric with the crank-axis. It is not essential that the 70 wheels O and P should be toothed. They might be plain untoothed wheels.

In the modification shown at Fig. 7 the pump or engine is made double—that is, two 75 pumps or engines, such as shown at Figs. 1, 3, or 5, are placed together, while the pistons B, instead of being made to fit at all times against a point, A^x, of the casing, are made to fit at all times one against the other. The 80 two pistons are also set, as shown, so that when one piston is parallel with the crank-arms which carry it, the other piston is at right angles thereto, so as to equalize the flow of fluid through the pump or engine. The movement of each of the pistons may be controlled in either of the ways hereinbefore described. 85

Figs. 12 and 13 show each piston provided with guides K K, as in Fig. 1, and these receive blocks L L, turning on stationary pins 90 M M. The two sets of blocks, L L, are in different planes.

Having thus described the nature of my invention and the manner of performing the same, I would remark that I am aware that it 95 has before been proposed to construct engines or pumps with a piston carried by the pin of a crank revolved in a casing of a form approaching somewhat to a cardioidal form; but in this case the extremities of the side edges 100 only of the piston were made to fit up to the curved interior of the casing. With such a construction the size of inlet and outlet ports which could be used was of necessity extremely limited; but by making the extremity of the 105 inward bend of the casing to fit to the sides of the piston-ports of large dimensions may be employed, as in this way a division is always formed between the two ports. Also, by making the casing with the curve bending inward 110 at one point to make a heart-shaped figure, I am able to make the piston of much less width than would otherwise be practicable.

The improved means hereinbefore described 115 for controlling the movement of the piston also enables the movement of the piston to be more efficiently controlled than heretofore.

I would further remark that my invention in no way relates to engines in which the piston has a sliding movement through the axis 120 or revolving part which carries it. In my engine the piston has no other motion than rotary about the crank-pin upon which it is mounted.

What I claim as my improvements in rotary 125 pumps and engines is—

1. The combination of a cardioidal casing, A, a crank-axis, D, and crank-pin C, revolved therein, a piston, B, mounted upon the crank-pin, and caused to make one-half a revolution 130 for each revolution of the crank-axis, and an inlet-port, E, and outlet-port F, separated by

the inward bend A^x of the casing, such inward bend being made to fit to the piston, substantially as described.

2. The combination of a cardioidal casing, A, a crank-axis, D, and crank-pin C, revolved therein, a piston, B, mounted upon the crank-pin, a tubular neck, B', projecting from one end of the piston and carried through a disk, H, which is concentric with the crank-axis, and is capable of revolving in an aperture in the end of the casing, and mechanism situated outside this disk for causing the piston B to make one-half a revolution for each revolution of the crank-shaft.

15 3. The combination of a cardioidal casing, A, a crank-axis, D, and crank-pin C, revolved therein, a piston, B, mounted upon the crank-pin, pairs of guide-bars K, carried by the piston, and blocks L, received between the guide-

bars, and capable of turning on pins M, to control the movement of the piston, substantially as described.

4. The combination of a cardioidal casing, A, a crank axis, D, and crank-pin C, revolved therein, a piston, B, mounted upon the crank- 25 pin, pairs of guide-bars K, carried by the piston-blocks L, received between the guide-bars, and capable of turning on fixed pins M, a bar, N, carried by one or both pins M, and an arm, C^x, on the end of the crank-pin C, carrying a 30 pin concentric with the crank-axis, which pin is received into a bearing in the bar N, substantially as described.
